UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

OPERATING DEVICE FOR CAR COUPLERS

Application filed March 16, 1928. Serial No. 262,298.

The invention relates to devices for operating railway car couplers.

The Interstate Commerce Commission safety appliance standards require that a railway car be equipped with means to "operate" a coupler from adjacent the side of the car. "Operating" consists of unlocking the coupler, throwing the knuckle to open position or raising the lock to lock-set position. A railway car is usually provided with a rod operatively connected to the car coupler and revolvably supported by the car body and provided with a depending handle adjacent the side of the car which is used to revolve the rod. The relative position of such handle to the side of the car is specified in said safety appliance standards.

An object of the device is to provide an arrangement wherein the operating rod may move longitudinally of itself to accommodate the lateral movements of the coupler in service without materially moving the depending handle of the operating rod;

In the drawings:

25 Figs. 1, 2 and 3 show a typical application of my device to a railway car.

Figs. 4 to 7 inclusive are typical cross sections of operating rods.

Figs. 8 and 9 show modified forms of the handle.

Fig. 10 shows a typical application of my device to a railway car.

Figs. 1, 2 and 3 show the preferred form wherein the bracket 2 is supported by the car body and the handle or lever 3 is hinged to the bracket so as to move only in a vertical plane longitudinally of the car, and an aperture 4 is provided in this handle through which the operating rod 5 slidably extends. Both the aperture 4 and the cross section of the operating rod 5 are non-circular so as to provide a non-rotative connection between these two elements so that when the handle 45 is swung the operating rod is revolved.

Figs. 4, 5, 6 and 7 show various non-circular sections of operating rods which could be used and the aperture in the handle would be correspondingly shaped to provide a non-rotative connection therebetween. The op-

erating rod is straight for a short distance on either side of the handle so that it may move longitudinally of itself through the aperture without swinging the handle.

Fig. 8 shows the handle or lever formed in a bell crank, the longer arm 7 thereof constituting a handle and the shorter arm 8 thereof supporting and being connected to the operating rod 5 which projects through the aperture 9.

In the design shown in Fig. 9 the operating rod 5 passes through the aperture 10 forming a non-rotative connection therewith, which connection is above the pivot 13 and handle 12.

The Interstate Commerce Commission safety appliance standards require that the coupler operating rod "handles shall not be more than twelve (12), preferably nine inches (9''), from sides of cars." This provision is made so that the operating rod handle will be in substantially the same position relative to the side of the car at all times so that the brakeman or switchman can readily catch hold of it in the dark or without looking for it, which is essential on slippery ground, therefore, I prefer to arrange my device so the operating rod can move longitudinally of itself without materially swinging the handle.

The accompanying drawings illustrate the preferred form of the invention, though it is to be understood that the invention is not limited to the exact details of construction shown and described, as it is obvious that various modifications thereof within the scope of the claims will occur to persons skilled in the art.

1. An operating device for a railway car comprising a handle hingedly mounted upon the car to swing only in a plane substantially longitudinal of the car, and an operating rod having a slidably non-rotative connection with said handle eccentric from the axis of the handle.

2. An operating device for a railway car coupler comprising a handle hingedly mounted upon the car to swing only in a plane substantially longitudinal of the car and having a non-circular aperture therein, eccentric from

the axis of the handle, and an operating rod provided with a non-circular portion slidably passing through said aperture so as to provide a slidable non-rotative connection with said handle.

3. An operating device for a railway car coupler comprising a depending lever arm hingedly mounted upon the car to swing only in a plane substantially longitudinal of the car, said lever arm carrying a non-circular aperture removed from the axis of the lever arm and lying in the plane of movement of said lever arm, and an operating rod operatively attached to a coupler having a non-circular portion slidably passing through said aperture so as to provide a slidable non-rotative connection with the lever arm.

4. An operating device for a railway car coupler comprising a depending lever arm hingedly mounted upon the car to swing only in a plane substantially longitudinal of the car, said lever arm provided with a lateral extension forming a bell crank carrying a non-circular aperture and lying in the plane of movement of said lever arm, and an operating rod operatively attached to a coupler having a non-circular portion slidably passing through said aperture so as to provide a slidable non-rotative connection with the lever arm.

5. An operating device for a railway car coupler comprising a depending lever arm hingedly mounted upon the car to swing only in a plane substantially longitudinal of the car, said lever arm carrying a non-circular aperture above the axis of the lever arm and lying in the plane of movement of said lever arm, and an operating rod operatively attached to a coupler having a non-circular portion slidably passing through said aperture so as to provide a slidable non-rotative connection with the lever arm.
